UNITED STATES PATENT OFFICE.

ZENUS L. HURD, L. D. HURD, AND CYRUS G. HURD, OF NASHVILLE, TENNESSEE.

LADDER-FOOT.

1,119,081.

Specification of Letters Patent.

Patented Dec. 1, 1914.

Application filed April 2, 1914. Serial No. 829,094.

To all whom it may concern:

Be it known that we, ZENUS L. HURD, L. D. HURD, and CYRUS G. HURD, citizens of the United States, residing at Nashville, in the county of Davidson and State of Tennessee, have invented certain new and useful Improvements in Ladder-Feet, of which the following is a specification, reference being had to the accompanying drawings.

10 This invention relates to certain improvements in ladders and has relation more particularly to an attachment therefor; and the object of the invention is to provide a device of this general character wherein is afforded an effective means whereby such leg is prevented from slipping and from marring the surface on which it may rest.

The invention consists in the details of construction and in the combination and arrangement of the several parts of our improved ladder whereby certain important advantages are attained and the device is rendered simpler, less expensive and otherwise more convenient and advantageous for use, all as will be hereinafter more fully set forth.

The novel features of the invention will be carefully defined in the appended claim.

In order that our invention may be the better understood, we will now proceed to describe the same with reference to the accompanying drawings, wherein—

Figure 1 is a view in rear elevation of an attachment constructed in accordance with an embodiment of our invention. Fig. 2 is a sectional view taken substantially on the line 2—2 of Fig. 1; Fig. 3 is a sectional view taken on a line substantially at right angles to the section disclosed in Fig. 2; Fig. 4 is a section taken substantially on the line 4—4 of Fig. 1; and Fig. 5 is a view of a device of a somewhat different design but constructed substantially as disclosed in the preceding views.

45 As disclosed in the accompanying drawings, 1 denotes a frame of requisite construction having projecting upwardly therefrom and integrally produced therewith, the bars or arms 2 of predetermined length and integrally produced with the upper extremities of such arms or bars is a second frame 3, such frames 1 and 3 being of a configuration substantially similar to the form of the leg in cross section to which the device is adapted to be applied, and the upper frame 3 is adapted to snugly accommodate such leg.

The side bars 4 of the frame 3 are disposed on downward curves while one of the end bars 5 of the frame 3 is projected upwardly, as indicated at 6, and such end bar is provided with a threaded opening 7 through which is adapted to be adjusted the elongated pointed member 8 provided at its outer extremity with the milled head 9. It is to be observed that the member 8 is of such a length as to cause the pointed extremity 10 thereof to so penetrate or impinge the adjacent face of a leg as to effectively maintain the device or attachment against displacement.

70 The lower frame 1 is provided with a filler block 11 preferably formed of canvas webbing and with which the lower end or face of the leg is adapted to contact and suitably secured to the under face of such filler block 75 11 is a layer 12 of soft rubber having its outer face serrated or corrugated, as indicated at 14. This layer 12 is disposed below and exteriorly of the lower frame 1 and serves as an effective means to prevent slipping or skidding of the leg and also serves to prevent marring of the surface on which such leg may be supported, especially when the ladder, of which the leg forms a part, is rested upon a polished surface.

75 In order to maintain the filler block 11 against displacement, we herein show the same as securely maintained in operative position through the medium of the rivets 15 disposed transversely of the frame 1.

90 From the foregoing description, it is thought to be obvious that a ladder attachment constructed in accordance with an embodiment of our invention is of an extremely simple and comparatively inexpensive nature and is particularly well adapted for use by reason of the convenience and facility with which it may be assembled and by reason of the effectiveness with which it performs its functions, and it will also be obvious that our invention is susceptible of some change and modification without material departure from the principles and spirit thereof and for this reason we do not wish to be understood as limiting ourselves to the 95 precise arrangement and formation of the several parts herein shown in carrying out our invention in practice.

100 We claim:

110 In a ladder foot, the combination of a metallic holder having its upper and lower faces open, a yieldable pad inserted in the

lower open face of the holder and projecting therebeyond, retaining means for the pad disposed transversely through the holder and pad, an end of the holder being provided with an extension projecting above the open face of the holder, and a clamping screw threaded through the extension.

In testimony whereof we hereunto affix

our signatures in the presence of two witnesses.

10
